ciete Francaise Sadir-Carpentier, Paris, France,
a corporation of France

Application April 12, 1951, Serial No. 220,654

Claims priority, application France April 14, 1950

6 Claims. (Cl. 346—112)

1

Our invention relates to a disturbance-recording system of the type wherein the record on paper that is produced only when the disturbances have appeared, carries a record of the modifications of the magnitude to be examined during the time that has preceded said disturbances and our invention covers more particularly improvements to the inking means for such disturbance-recording systems.

The disturbance-recording systems of the type disclosed are intended for the recording of modifications of any phenomena, the rate of which is given out by the movement of a hand or stylus when one or more of the phenomena considered or other phenomena assume fortuitously abnormal values and they allow the recording of these phenomena during a time interval of which a fraction precedes the moment of the appearance of such phenomena having an abnormal fortuitous value.

Such phenomena are generally constituted by electrical magnitudes the variations of which it is desired to examine at the moment of the appearance of a disturbance.

The principle of our improved method consists in executing, as long as the system or instrument is operative, a record of the variations of the electric magnitude or magnitudes to be studied, said magnitude or magnitudes controlling the shifting of a stylus along a line parallel to the generating line of a cylinder rotating with a constant speed round its axis and that is suitably coated with a fatty ink material.

The record thus drawn on the cylinder is wiped out a few moments later, when the generating lines of the cylinder over which the record has been made, return under the action of the rotation of said cylinder, into the stationary meridian plane in which the cylinder is inked.

The record carried by the cylinder remains extant during a predetermined time interval θ depending on the duration required for a given generating line of the cylinder to move from the stationary meridian plane in which the stylus moves and the stationary meridian plane in which the inking is provided.

The appearance of an electrical disturbance in the network leads to the operation of a releasing electromagnet the armature of which is attracted and has for its action to apply, through any suitable means, a sheet of record paper onto the inked cylinder so as to reproduce on the paper in white on black, the record drawn on the inked cylinder before the latter has been wiped out by the inking means.

2

If a generating line requires a duration t less than θ for its movement with the rotary cylinder, from the meridian plane containing the recording stylus, into the meridian plane containing the recording sheet of paper urged against said cylinder, there is obtained a record on paper of the modifications of the magnitude or magnitudes to be studied during a time t preceding the attraction of the armature of the electromagnet, in other words, the moment at which the disturbance appears.

Through a suitable adjustment of the circuits providing for the attraction of the releasing relays, the sheet of paper may be held against the cylinder during a time t' , that is always longer than t , following the appearance of the disturbance so as to allow the recording of the variations of the magnitude or magnitudes to be examined during this time interval t' : this time interval includes a duration t that precedes the appearance of the disturbance and a period the duration of which is $t'-t$ following the appearance of said disturbance.

Studies made by applicant have shown that in the long time intervals during which the instrument was operative without any disturbances appearing in the network, it was necessary to limit the thickness of the ink film laid on the cylinder if it was desired to prevent a speedy fouling of all the members of the instrument while allowing the production of a uniform ink layer.

The amount of ink laid onto the cylinder should be substantially limited to an amount approximating that required for leaving a sufficient ink film allowing the recording of the variations of the magnitude or magnitudes to be examined in the absence of any disturbance in the network, said film being produced while a generating line, inked during its last passage through the meridian plane in which the inking arrangement is provided, moves out of said plane into the meridian plane in which the recording stylus moves.

Now, when a disturbance appears in the network, the consumption of ink increases very suddenly, as part of the ink is transferred onto the recording paper and consequently, if for any reason such as a longer duration of the disturbance, the time interval during which the recording is formed is comparatively high, the inking is not sufficient and the printing on the record paper becomes blurred, soon turns illegible and even disappears.

In order to remove this drawback, our invention covers an improvement in disturbance recorders of the type described above, according to

which means are provided for increasing the amount of ink laid on the cylinder as soon as the disturbance appears in the network, in order to compensate for the increased consumption of ink that is a consequence of the application of the record paper onto the inked cylinder and also with a view to producing a clear record, whatever may be the duration t' during which the recording is performed on the paper strip. Said duration t' depends on the duration of the disturbance and may be limited to a duration T' when the duration of the disturbance rises above a predetermined value.

To this end, the attraction of the armature of the electromagnet that controls the application of the record paper onto the inked cylinder produces also an increase in the amount of ink applied to said cylinder.

Our invention will be described hereinafter within the scope of an embodiment illustrated diagrammatically in the single figure of accompanying drawing, but obviously our said invention is not limited to this particular case and covers any disturbance-recording means incorporating an arrangement for increasing the admission of ink onto the inked cylinder during the transfer of the record on paper.

Auxiliary cylinders 4 and 5 are employed to apply ink onto the cylinder 1 along the upper generating line of which, as illustrated, the stylus or styluses 2 move in accordance with the variations of the magnitude or magnitudes to be examined. The stylus 2 is controlled by the member or members 3.

A system of pens 6 or the like parts such as cups, metal blades or wire eyelets executes a reciprocating movement between the ink container 7 and the cylinder 5 so as to feed a little ink onto the cylinder 5. This cylinder transfers the ink frictionally onto the cylinder 4 that revolves in contact with the main cylinder 1. The relative rolling movement of the three cylinders 5, 4 and 1 with reference to one another provides for the spreading of the ink brought onto the cylinder 5 by the pens 6. A helical groove drawn on the cylinder 5 allows increasing the uniformity of the layer of ink applied to the cylinder 1.

The reciprocation of the pens 6 is obtained by securing said pens through the agency of yielding rods to a mechanical system or linkage 8 that is adapted to oscillate about the pivot 11. This linkage 8 includes a lever 10 that is connected by a spring 13 to the wheel 9 driven in unison with the cylinders 1, 4 and 5, so as to assume a uniform rotary movement under the action of the motor driving the system, said motor not being illustrated.

According to our invention, there are provided two pen systems 6' and 6'' located at two different heights whereby, when the shifting of the mechanical system 8 is limited, only a single pen system 6' comes into contact with the cylinder 5 while, when the shifting of said mechanical system is substantial, the two pen systems 6' and 6'' engage the cylinder 5 so as to produce a larger transfer of ink.

According to an important feature of this invention, the attraction provided by the electromagnet 23 on the armature 22 which functions to apply the record paper 26 onto the inked cylinder also functions to shift a stop 16 upwardly. Prior to being shifted upwardly the stop 16 limited the movement of the mechanical linkage 8. When shifted the stop 16 permits inking of the cylinder 5 through both pen systems 6' and 6'',

because the linkage 8 may swing through a larger angle thereby permitting both pens 6' and 6'' to come into contact with the cylinder 5.

By way of an example, we may mention that the mechanical system 8 may be constituted by a rigid bar 10, to the stationary pivoting point 11 of which are secured resilient parts carrying the pens 6' and 6''. The bar 10 is connected, furthermore, through a pivotal connection 12 to a spring 13, the other end of which is connected by a rod 14 to an eccentric point 15 of the wheel 9.

The stop 16 is connected, preferably through the agency of a linkage 17-18-19 of which the pivot 19 is secured to the frame, with the metal rod 20 forming one of the arms of a lever system rockably carried by the pivot 21 also secured to the frame. The armature 22, associated with the electromagnet 23, is connected to the rod 20.

A projecting arm 24 on said lever system is secured, furthermore, to the axial spindle carrying the cylinder 25 around which is wound the paper strip 26 fed by the roller 21.

When the winding of the relay 23 is de-energized, the record paper 26 is no longer in contact with the cylinder 1 and the stop 16 limits the movement of the bar 10 and limits thereby the transfer of ink onto the cylinder 5.

As soon as the winding of the electromagnet 23 is energized as a consequence of the appearance of a disturbance for instance, the lever arms 24-20 are rotated about the pivot 21 since the electromagnet 23 attracts the armature 22 and the two following results are obtained: on one hand, the record paper 26 is applied against the cylinder 1 and the actual recording is obtained on said paper; on the other hand, the stop 16 is shifted upward and no longer limits the amplitude of movement of the rigid bar 10; consequently, the movement of said bar assumes a sufficient amplitude for urging both of the pens 6' and 6'' into contact with the cylinder 5 during the periodic movement imparted to the pen system by the wheel 9. This results in increased transfer of ink onto the cylinder 5, when the electromagnet is thus energized.

Of course, numerous detail modifications may be made in the arrangement disclosed without thereby unduly widening the scope of the invention as defined in accompanying claims. In particular, it is possible to resort to independent inking means of which one is used permanently and the other becomes operative only when the controlling electromagnet armature is attracted.

What we claim is:

1. A disturbance-recording system comprising a main rotary cylinder, three operative stations adapted to engage the circumference of said cylinder along three lines parallel with the axis of said cylinder, said three operative stations including, in the direction of rotation of said cylinder, in succession: inking means for inking the circumference of said cylinder, recording means submitted to the action of outer phenomena, and record transferring means, and means submitted to the action of the disturbances and adapted, when operative, to simultaneously urge said record-transferring means into operative contact with the inked surface of said cylinder and to control said inking means for increasing the delivery of ink to the circumference of said cylinder.

2. A disturbance-recording system comprising a main rotary cylinder, three operative stations adapted to engage said cylinder along three lines parallel with the axis of the cylinder, said three operative stations including, in the direction of

rotation, in succession: inking means for inking the circumference of said cylinder, recording means submitted to the action of outer phenomena, and record-transferring means, and electro-magnetic means energized in accordance with the disturbances and adapted, when operative, to simultaneously urge said record-transferring means into operative contact with the inked surface of said cylinder and to control said inking means for increasing the delivery of ink to the circumference of said cylinder.

3. A disturbance-recording system comprising a main rotary cylinder, three operative stations adapted to engage said cylinder along three lines parallel with the axis of the cylinder, said three operative stations including, in the direction of rotation, in succession: an inking roller system for inking the circumference of said cylinder, recording means submitted to the action of outer phenomena and record-transferring means, two inking pens adapted to operatively engage said inking roller system, means rotating in unison with said cylinder for periodically engaging one of said pens with said inking roller system and means submitted to the action of the disturbances and adapted, when operative, to simultaneously urge said record-transferring means into operative contact with the inked surface of said cylinder and to engage the other of said pens with said inking roller system for increasing transiently the delivery of ink to said cylinder.

4. A disturbance-recording system comprising a main rotary cylinder, three operative stations adapted to engage said cylinder along three lines parallel with the axis of the cylinder, said three operative stations including, in the direction of rotation, in succession: an inking roller system for inking the circumference of said cylinder, recording means submitted to the action of outer phenomena and record-transferring means, two inking pens, a link member carrying said pens, a rotary member rotating in unison with said cylinder, a resilient member controlling said link member and actuated periodically by last mentioned rotary member for urging said pens into engagement with said inking roller system, an abutment normally preventing the movement of said link member beyond the position for which only one of said pens engages said inking roller system and means submitted to the action of the

5
10

disturbances and adapted, when operative, to simultaneously urge said record-transferring means into operative contact with the inked surface of said cylinder and to shift said abutment to allow said link member to continue its movement and to engage the other of said pens in its turn against said inking roller system.

5. A disturbance-recording system comprising a main rotary cylinder, three operative stations adapted to engage said cylinder along three lines parallel with the axis of the cylinder, said three operative stations including, in the direction of rotation, in succession: inking means for inking the circumference of said cylinder, recording means submitted to the action of outer phenomena and record-transferring means, additional means for inking said cylinder along the same line as the first mentioned inking means and electro-magnetic means energized in accordance with the disturbances and adapted, when operative, to simultaneously urge said record-transferring means into operative contact with the inked surface of said cylinder and to make said additional inking means transiently operative.
